ATTORNEY

UNITED STATES PATENT OFFICE.

NOAH M. CHEW, OF SOUTHPORT, INDIANA.

PLANT-SETTING MACHINE.

SPECIFICATION forming part of Letters Patent No. 440,738, dated November 18, 1890.

Application filed March 24, 1890. Serial No. 345,013. (No model.)

To all whom it may concern:

Be it known that I, NOAH M. CHEW, of Southport, county of Marion, and State of Indiana, have invented certain new and useful 5 Improvements in Plant-Setting Machines; and I do hereby declare that the following is a full, clear, and exact description thereof, reference being had to the accompanying drawings, in which like figures refer to like parts.

10 My invention relates to the construction of plant-setting machines, and is an improvement on the device for which Letters Patent No. 406,336 were issued to me July 2, 1889, and will be understood from the following description.

15 In the drawings, Figure 1 is a top view. Fig. 2 is a sectional view on the line $\alpha\alpha$, Fig. 1. Fig. 3 is an enlarged detail view of the hinge by which the row-marker is connected 20 to the frame of the machine. Fig. 4 is an enlarged detail front view of the brackets carrying the covering-wheels, one of them being in section. Fig. 5 is an enlarged perspective view of the coupling mechanism and seat-frame.

25 The machine comprises a rear platform-section 1, upon which are seats or cushions 6 for the men who are to set the plants. This platform is supported upon a pair of covering-wheels 22, which are mounted upon stub-axles 21, connected with brackets 19, bolted to the under side of the platform on each side. In my former machine these wheels 30 were mounted upon the inside of the bracket-shank, the axles extending at an angle upward toward the platform, and the result was that when the soil was wet and the wheels sank therein the earth was crowded in against the shoulder of the axle, often packing there 35 and clogging the movement of the machine. By mounting the wheel upon the outside and elevating the end of the bracket where the axle is connected all packing of soil and clogging is prevented. This construction (shown 40 in Fig. 4 of the drawings) is greatly preferable to that shown in a similar figure in my former application. The rear platform 1 is provided with a seat 9 for the driver, which is adjustably set on the frame-work 8, having 45 an open slot, as shown in Figs. 2 and 5, so that the driver by the mere movement of his body can draw the seat forward or push it

backward, adjusting it, as may be desired, so as to bring his weight either over the end of the furrow-marker and sink it deeper into the ground or back over the covering-wheels, thereby raising the furrow-marker out of the ground. This is another improvement upon my former patent. This seat-frame 8 is connected by brace-rods 7 to the rear coupling-bar 5, which is formed integral with the bar 4, having short axles or gudgeons on either side journaled in arms 3, connected to the bars 2, that connect the two parts of the platform, so as to allow a rocking movement upon 60 these axles for the rear or platform section of the machine. This rear section is also connected to the front section 11 by bars 2, which are hinged at 26 to the board 12 of the front section of the machine, this section being composed of the boards 11 and 12, and the furrow-markers 27 are connected beneath, as shown in Fig. 2, so that this part of the machine rests directly upon these furrow-markers. 70

75 24 is a link by which connection is made between the front draft-beam 23 and the rear coupling-beam 5, the former passing under the latter in the manner shown in Figs. 2 and 5, so that when the driver shifts his seat forward the weight of his body operates upon the beam 5, which rests upon the beam 23, to crowd the furrow-marker farther into the ground. This beam 23 is stayed to the bars 2 by braces 28, and the boards 11 and 12 are 80 also connected together by diagonal braces 29.

85 80 30 are foot-rests for the plant-setters. The draft-beam 23 is extended forward to form a tongue, and a doubletree is connected thereto by a hammer strap and pin in the usual manner. 90

95 At the rear of the machine I attach a row-marker 18, which is intended to mark the line for the next row, so as to space the rows the proper distance. It is shown in Fig. 1 as connected to the right side; but it may be connected to either side of the machine. It consists of a piece 18, connected by an arm to a coupling device 16, hinged in the slotted end of the bar 15, fastened to the platform, 100 the detail of this being shown in Fig. 3, and for coupling this the marker is raised, so that the T end will pass down into the slot of the bar 15, making a connection that cannot be

loosened until the marker is thrown up at the proper angle.

The furrow-marker or plow 27 is constructed in the manner shown and described in my former patent and needs here no further description other than to say that the plant is intended to be set between its open rear ends, which are widened for that purpose.

Below the driver's seat 9 is fixed a board 14, 10 which rests upon the cross-bars 2, and a box is thus formed directly beneath the driver's seat within easy reach of the workmen sitting on the cushions 6 on either side. I thus avoid the necessity of providing a box for holding 15 the plants upon the forward part of the machine, as shown in my former device.

My machine operates as follows: The team is hitched to the doubletree and the driver takes his seat at 9. The plants are placed in 20 the box beneath the driver's seat and the plant-setters sit upon the cushions 6. The furrows are made by the plows 22, and the operator, taking a plant from the box, places it and the furrow thus formed between the 25 separated ends of the furrow-marker. The covering-wheels follow, filling in the earth on each side and pressing it firmly, and the driver, by shifting his seat, can bring his weight down so as to force the furrow-marker deeper 30 into the ground, and by shifting his seat back can raise it out of the ground.

By the use of this device a great deal of time and labor is saved and a large number of plants can be set in a day, and by the improvements herein shown the objections to 35 my former machine are entirely removed. The rear section is easily swung up upon the hinges 26, and all parts are flexible and work easily as related to each other.

40 What I claim as my invention, and desire to secure by Letters Patent, is the following:

1. In a plant-setting machine, a platform providing seats for the workmen, mounted upon brackets on each side carrying a pair of covering-wheels, a forward section beneath 45 which are secured furrow-marking plows on each side hinged to a cross-bar connected to the rear platform and also connected to such

rear section by a link uniting the draft-bar to a rear bar which normally rests upon the 50 draft-bar, and a seat-frame connected to such rear bar and provided with an adjustable seat, whereby the weight of the driver may be shifted from the covering-wheels to the furrow-markers or from the latter back to the 55 former, substantially as shown and described.

2. A plant-setting machine whose framework is composed of two sections hinged together, the rear section providing a working-platform mounted upon pairs of covering-wheels having seats for the workmen, the forward section mounted upon furrow-marking plows, a row-marker for centering the next series of rows, detachably connected to the rear platform and on one side, and a driver's seat 60 movable on a frame-work connected thereto for adjusting his weight forward and backward, as desired, all combined substantially as shown and described.

3. In a plant-setting machine, a frame-work 70 composed of two sections hinged together, the rear section forming a platform having seats for the workmen, such platform supported upon pairs of covering-wheels mounted on axles connected to brackets bolted beneath 75 the frame-work, such axles set at an angle to the shank and so disposed that the wheels are mounted upon the outside of such shank, the forward sections mounted upon furrow-marking plows, and the driver's seat movable on a frame-work connected to the machine for 80 adjusting his weight forward or backward, as desired, all combined substantially as shown and described.

4. In a plant-setting machine, a row-marker 85 18, detachably connected to the rear platform-section on either side by means of the couplings 16, and slotted bar 15, connected to the frame, substantially as shown and described.

In witness whereof I have hereunto set my 90 hand this 7th day of March, 1890.

NOAH M. CHEW.
